AUTOMATIC BURGLAR, FIRE, OR LIKE
ALARMEdred Rabjohn Mountstephen, Southend-on-
Sea, EnglandApplication January 31, 1938, Serial No. 187,960
In Great Britain February 15, 1937

6 Claims. (Cl. 179—5)

This invention relates to automatic burglar and fire alarms and more particularly of the kind comprising a gramophone or like sound reproducing device operatively connected with a telephone and associated with means automatically to establish communication with a police, fire or other station and to transmit a suitable message or signal to said station upon the occurrence of a burglary or fire. An alarm of this kind is described in my co-pending application Serial No. 172,461.

The object of the present invention is to provide an alarm of this kind which discriminates between fire and burglary, that is to say which is designed automatically to produce and transmit an appropriate alarm message or signal according to whether a burglary or fire has occurred, and the invention therefore consists broadly of an alarm apparatus of the kind whereupon the occurrence of an emergency, an alarm is transmitted over a telephone circuit to a receiving station, characterised in that provision is made for the transmission of alternative alarm messages or signals according as the emergency is occasioned by burglary or fire.

The preferred method by which the desiderata can be attained is illustrated in the accompanying drawings wherein:

Figure 1 is a plan view of the alarm according to the aforesaid co-pending application as modified in accordance with the present invention.

Figure 2 is a part sectional elevation of the modified part of the apparatus according to the present invention looking in the direction of the arrow II in Figure 1.

Figure 3 is a plan view on an enlarged scale of the mechanism illustrated in Figure 2, and

Figure 4 is a diagram of the wiring circuit.

Referring first to Figure 1 the general operation of the alarm device there illustrated is as follows: An electromagnet 5 is energised by mechanical action in any known manner, upon the unauthorised opening of a door, window, safe or the like or by the action of a thermostat upon

an abnormal rise in temperature, whereby trip mechanism 6, 7 is operated and a weighted lever 8 thereby released. The lever 8 then falls and during its fall first moves a catch 9 out of engagement with a stop 10 on the gramophone turntable to start the gramophone motor and then closes a switch 11 to connect the alarm device with the telephone system. The gramophone motor thus being set into operation drives transmission mechanism indicated generally at 12, which then operates the dialling mechanism

13 to establish communication with the desired station, after which the sound box 14 is gradually lowered onto the sound record, whereupon the alarm message or signal is transmitted to the police, fire, or other station with which communication has been established. When the sound box 14 reaches the end of its travel across the record it is then lifted and returned to the commencement of the record when the alarm message or signal is again produced and transmitted to the desired station. This operation is repeated continuously until the gramophone motor runs down when a knife switch 15, controlled by the governor of the gramophone motor, operates to close the circuit of an electromagnet 16 which is thus energised and releases a catch 17 whereby the switch 11 is opened and the device thus disconnected from the telephone system.

The construction, arrangement and operation of the various parts above referred to is as described in detail in the aforesaid co-pending application.

According to the illustrated embodiment of the present invention the sound record is provided with two separate recordings or messages, one appropriate to burglary on the first half of the record and another appropriate to fire on the second half of the record and spring actuated mechanism is provided which, in the event of fire, is automatically set into operation to move the sound box from its normal position above to commencement of the first half of the record, to a second position above the commencement of the second half of the record before being lowered onto the said record in the usual way. This mechanism is set into operation by an electromagnet 18 which is arranged in the circuit of a thermostat or the like which, upon an abnormal rise in temperature, closes the circuit of the electromagnet 18 (as well as the electromagnet 19), which is thus energised and releases a trip to set into operation the spring actuated mechanism which is shown more clearly in Figures 2 and 3.

Referring more specifically to Figures 2 and 3, the sound box unit, comprising the sound box, tone arm and microphone housing, preferably of the character described in my co-pending application Serial No. 172,462, is mounted on a vertical rod 19 rotatably mounted in a member 20 which is itself pivoted at 21 to a bracket 22, whereby said tone arm unit can pivot both in a horizontal plane, to enable the sound box to move across the sound record, and in a vertical plane, to enable the sound box to be lowered onto

and lifted from said record. On the lower end of the rod 19 is a cross-bar 19a or the like which, when the sound box is in its raised position above the sound record, lies parallel to and engages a plate member 23. The plate member 23 is secured to a sleeve 24 rigidly mounted on shaft 25 which extends through the base plate 26 of the apparatus and is rotatably mounted in a bracket 27 and the base plate 26. Rigidly secured on the shaft 25, below the base plate 26 is a second sleeve 28 from which extends a radial arm 29, the outer free end of which engages the armature 30 of the electromagnet 18 and is normally held pressed against said armature by a spring 31.

In the normal position of the parts, as shown in full and dotted lines in Figure 3, the sound box is located above the commencement of the first half of the sound record, that is to say above that part of the record containing the recording or message appropriate to burglary, and if a burglary occurs the electromagnet 5 only is energised and the gramophone motor is started, as described above, whereupon the alarm operates exactly as described in the co-pending application Serial No. 172,461. In the event of a fire, however, the electromagnet 18, as well as the electromagnet 5, is energised by the action of a thermostat whereupon the gramophone motor is started to effect the normal operation of the alarm and in addition the armature 30 of the electromagnet 18 is attracted and releases the arm 29 which is then moved by the spring 31 against a stop 32. This angular movement of the arm 29 causes rotation of the shaft 25 which in turn causes an angular movement of the plate member 23 which, due to its engagement with the cross-bar 19a, rotates the rod 19 upon which the sound box unit is mounted. Thus the sound box itself is moved over the sound record. The amount of movement of the parts 29, 25, 23 and 19 is limited by the stop 32 and is such that the sound box 14 is moved over only half the sound record. After the sound box has been moved into position above the commencement of the second half of the sound record in this way, it is lowered onto the record exactly as described in the co-pending application.

It will be clear from the foregoing that if the alarm is set into operation by mechanical action, that is by the making or breaking of a circuit due to the unauthorised opening of a door, window, safe or the like, i. e. in the event of a burglary, the parts shown in Figure 3 remain in their normal position, shown in full and dotted lines, and the sound box is lowered onto the commencement of the first half of the record in the usual way but if the alarm is set into operation by thermal conditions, that is by the action of a thermostat or the like in the event of fire, the parts are moved into the position shown in chain dotted lines in Figure 3 by the spring 31, the arm 29 being released by the electromagnet 18, before the sound box is lowered onto the commencement of the second half of the record.

The circuit of the alarm device shown diagrammatically in Figure 4 is the same as in the co-pending application except that the additional electromagnet 18 is connected in series with the electromagnet 5, the arrangement being such that in the event of a burglary the contacts b, c are connected by a suitable switch (not shown) whereby the circuit of the electromagnet 5 only is closed but in the event of fire the contacts a, c are connected by a thermostat (not shown)

whereby the circuit of the electromagnets 5 and 18 are closed.

Since the greater part of the mechanism which operates to select the alarm message or signal is located below the base plate 26 of the apparatus (see Figure 2), it is necessary to provide an aperture in the base plate for giving access to the arm 25 so as to facilitate resetting after this arm has been released by the electromagnet 18.

What I claim and desire to secure by Letters 10 Patent is:

1. In combination, a gramophone turntable, a record disk on said turntable having a pair of annular record bands concentrically disposed, motor means for driving said turntable, a tone arm carrying a sound box, a vertical shaft, a tone arm support mounted on said shaft, to swing in a horizontal plane, said tone arm being mounted pivotally on the support to swing in a vertical plane, means controlled by the motor means for raising and lowering the tone arm, and means to cause rapid traverse of the tone arm over the outer record band while the tone arm is raised.

2. In combination, a gramophone turntable, a record disk on said turntable having a pair of annular record bands concentrically disposed, motor means for driving said turntable, a tone arm carrying a sound box, a vertical shaft, a tone arm support mounted on said shaft to swing in a horizontal plane, said tone arm being mounted pivotally on the support to swing in a vertical plane, means controlled by the motor means for raising and lowering the tone arm, means to cause rapid traverse of the tone arm over the outer record band while the tone arm is raised, and alarm circuit controlled means for rendering the last mentioned means ineffective.

3. In combination, a gramophone turntable, a record disk on said turntable having a pair of annular record bands concentrically disposed, motor means for driving said turntable, a tone arm carrying a sound box, a vertical shaft, a tone arm support mounted on said shaft to swing in a horizontal plane, said tone arm being mounted pivotally on the support to swing in a vertical plane, means controlled by the motor means for raising and lowering the tone arm, an actuating arm operatively connected to the vertical shaft, a spring urging said actuating arm in a direction to move the sound box inwardly of the record disk, a latch member normally holding said actuating arm against movement by the spring, and an alarm circuit including an electromagnet acting when energized to trip the latch member and release the arm.

4. In combination, a gramophone turntable, a record disk on said turntable having a pair of annular record bands concentrically disposed, motor means for driving said turntable, latch means restraining the motor means from operation, and an alarm circuit controlled magnet for releasing said latch means, a tone arm carrying a sound box, a vertical shaft, a tone arm support mounted on said shaft to swing in a horizontal plane, said tone arm being mounted pivotally on the support to swing in a vertical plane, means controlled by the motor means for raising and lowering the tone arm, and means to cause rapid traverse of the tone arm over the outer record band while the tone arm is raised.

5. In combination, a gramophone turntable, a record disk on said turntable having a pair of annular record bands concentrically disposed, motor means for driving said turntable, latch means restraining the motor means from opera-

tion, and an alarm circuit controlled magnet for releasing said latch means, a tone arm carrying a sound box, a vertical shaft, a tone arm support mounted on said shaft to swing in a horizontal plane, said tone arm being mounted pivotally on the support to swing in a vertical plane, means controlled by the motor means for raising and lowering the tone arm, means to cause rapid traverse of the tone arm over the outer record band while the tone arm is raised, and alarm circuit controlled means for rendering the last mentioned means ineffective.

6. In combination, a gramophone turntable, a record disk on said turntable having a pair of annular record bands concentrically disposed, motor means for driving said turntable, latch means restraining the motor means from opera-

tion, and an alarm circuit controlled magnet for releasing said latch means, a tone arm carrying a sound box, a vertical shaft, a tone arm support mounted on said shaft to swing in a horizontal plane, said tone arm being mounted pivotally on the support to swing in a vertical plane, means controlled by the motor means for raising and lowering the tone arm, an actuating arm operatively connected to the vertical shaft, a spring urging said actuating arm in a direction to move the sound box inwardly of the record disk, a latch member normally holding said actuating arm against movement by the spring, and an alarm circuit including an electromagnet acting when energized to trip the latch member and release the alarm.

EDRED RABJOHN MOUNTSTEPHEN.
